UNITED STATES PATENT OFFICE.

GEORGE H. BARKLEY, OF CHICAGO, ILLINOIS.

NON-REFILLABLE BOTTLE.

1,176,808.

Specification of Letters Patent. Patented Mar. 28, 1916.

Application filed November 30, 1914. Serial No. 874,630.

To all whom it may concern:

Be it known that I, GEORGE H. BARKLEY, a resident of Chicago, in the county of Cook and State of Illinois, have invented certain 5 new and useful Improvements in Non-Refillable Bottles, of which the following is a full, clear, and exact description.

The invention relates to devices for preventing bottles from being refilled.

10 One object of the invention is to provide a device for preventing a bottle from being refilled, comprising improved means for securing it in the neck of the bottle. This object is attained by a simple lock which is 15 adapted to operate automatically to secure the device in the bottle neck when the device is inserted in the neck, thus saving the expense of making a permanent fastening or cementing the device in place.

20 A further object of the invention is to provide an improved device for preventing bottles from being refilled.

The invention consists in the several novel 25 features hereinafter set forth and more particularly defined by claims at the conclusion hereof.

In the drawings: Figure 1 is a vertical section of a bottle embodying the invention. Fig. 2 is a perspective of the separate parts 30 of the device. Fig. 3 is a section taken on line 3—3 of Fig. 1. Fig. 4 is a section taken on line 4—4 of Fig. 1. Fig. 5 is a section taken on line 5—5 of Fig. 1. Fig. 6 is a section showing a modification.

35 The bottle 10 is provided with a neck 11, and a shoulder 12 is formed in the neck. A valve-casing 14 is formed with an upstanding flange 15, the upper edge of which serves as a valve seat and is secured in the bottle 40 neck by a ring of cork 16 which forms a water-tight connection between the valve-casing and the surrounding portion of the bottle neck. The valve-casing is provided with a flange 17 on the top of the cork ring 16, and the cylindrical wall of the casing is 45 formed with indentations 18 which form guides for a disk valve 19, which is adapted to close upon the valve seat on flange 15. The valve-casing and valve are formed of 50 glass. The cork-ring, when compressed in the bottle neck, is forced into the depression 18, so that the said ring and valve-casing will be firmly held together. A ball-weight 55 20, also formed of glass, serves to hold the valve closed, except when the bottle is tilted downwardly considerably beyond the hori-

zontal, in which position liquid will not flow into the bottle. Plug 21 is formed with a conoidal surface 22. Before the weight will release the valve, it is necessary to tilt 60 the bottle so the weight will roll toward the mouth of the bottle and upwardly on the conoidal surface 22. The lower end of plug 21 fits against the flange 17 and thus holds the ring and flange in the bottle neck. This 65 plug is provided with an improved automatic locking-device consisting of a pair of studs 23 which are held in an opening 24 which extends transversely through the upper portion of plug 21 and a cork 25, which 70 extends between the inner ends of the studs 23, and yieldingly presses them outwardly. An internal annular channel or recess 26 is formed in the bottle neck and studs 23 are adapted to pass into said channel and form 75 a positive interlock between the plug 21 and the bottle neck. In placing the device in the bottle, it is only necessary to first place the valve and casing with its ring 16, the valve and weight in the bottle neck and then studs 23 are forced inwardly, so that they will not 80 project beyond the periphery of the plug and when thus held, the plug can be forced into the bottle neck. As the plug 21 is forced downwardly, the studs 23, as they 85 reach channel 26, will be forced into the channel by the resilient filling or cork 25 and thus the plug 21 will be automatically locked, as it is placed in proper position in 90 the bottle.

Plug 21 is formed with a ring portion 27, in which the conical guide 22 is formed, and with lateral openings 28, which permit the liquid, when the bottle is inverted, to pass around ball-weight 20 to and through 95 grooves 29 formed on the periphery of the upper portion of the plug. Adjacent the hole 24, the plug fits snugly in the bottle neck and ring 27, and portions between the grooves 29 also fit snugly in the bottle neck 100 so that the plug will be firmly positioned therein. The bottle neck is extended, as at 10^a, to receive a cork 30 for sealing the contents of the bottle until such time as it may be desired to pour liquid from the bottle. 105

A modification of the invention is shown in Fig. 6, in which the bottle neck is formed with a tapered portion 10^b and the valve-casing is similarly tapered as at 31 to fit 110 directly in the tapered portion 10^b on the bottle neck. In this case, the tapered por-

tion of the bottle is ground to form a true seat for the valve-casing.

- The invention thus exemplifies a non-refillable bottle, which is simple in construction, and which can be quickly assembled without the use of cement, or similar uniting means. The cork-ring around the valve-casing provides a convenient liquid-tight joint between the valve-casing and the bottle neck. By forming indentations in the glass valve casing, the disk valve 19 will be guided in the valve-casing so that it will always be seated or restored to the correct position by the weight 20.
- 15 The invention is not to be understood as restricted to the details set forth, since these may be modified within the scope of the appended claims, without departing from the spirit and scope of the invention.
- 20 Having thus described the invention, what I claim as new and desire to secure by Letters Patent, is:

1. The combination with a bottle, having a recess therein, of a hollow one-piece valve-casing formed of glass and having an upwardly facing valve-seat at its lower end, a valve on said seat and movable in the casing, means for guiding the valve on the casing, a one-piece plug fitting in the bottle-neck and having its lower end abutting against the upper end of said casing, and having a downwardly tapering opening in

its central portion, having ducts leading laterally to the side of the plug from said central opening and having ducts on its periphery leading upwardly from the laterally extending ducts to the top of the plug and having the central portion of its top closed, a weight disposed partly in the valve-casing and partly in the plug, locking means in the plug adapted to pass into said recess, and resilient means for forcing the locking means into the recess when the plug is inserted in the bottle.

2. The combination with a bottle, of a valve-casing having an integral upstanding flange on which a seat is formed, a valve on said seat, a weight for holding the valve closed, loosely held in the casing, a resilient ring between the side of the casing and the bottle neck, an outwardly extending flange on the upper end of the casing and overlying the resilient ring and a one-piece plug secured in the bottle neck above said valve-casing, having its lower end abutting against said flange and having a conoidal surface for the weight and openings for liquid leading from said surface, said weight being partly disposed in the casing and partly in the plug.

GEORGE H. BARKLEY.
